UNITED STATES PATENT OFFICE.

DANIEL SULLIVAN, OF ST. LOUIS, MISSOURI.

ANSWERING-BOARD.

1,277,152.

Specification of Letters Patent. Patented Aug. 27, 1918.

Application filed January 28, 1918. Serial No. 214,081.

To all whom it may concern:

Be it known that I, DANIEL SULLIVAN, a citizen of the United States, residing at the city of St. Louis, in the State of Missouri, 5 have invented certain new and useful Improvements in Answering-Boards, of which the following is a specification.

This invention is a new answering board and apparatus for use in connection therewith to obtain the answer.

10 The board contains or bears those features that are common to such articles, viz., the letters of the alphabet and the ordinal numbers beginning with zero and ending with 15 nine, and the words "Yes", "No", and "Good bye"; but the same are arranged in a more convenient and practical form than on other old and well known boards of this kind, the arrangement of the present board being such 20 as to facilitate the reading of the indications by the movable table.

Besides this the present board bears two pairs of mystical symbols, viz., one pair of sunbursts and another pair of winged 25 worlds, although other symbols may be used or the number of each may be varied.

In the use of the said board any arbitrary 30 signification desired may be attached to the said four mystical symbols, or from their appearance allegorical interpretations may be deduced.

One especial advantage of the present invention is that an indicating table is provided with a plurality of pointers instead 35 of only one as has heretofore been common, and another especial advantage of the said table is that its central spindle or foot is convex on its bottom, as are also the plurality of feet respectively provided for alternative use in lieu of the said central 40 spindle or foot.

In the accompanying drawings forming part of this specification, in which like numbers of reference denote like parts wherever 45 they occur,

Figure 1 is a perspective view of the operative surface of this board, the said view showing also the movable table or indicator at rest thereon at about the center;

50 Fig. 2 is a bottom plan view of the said indicator;

Fig. 3 is a sectional view on the line 3—3 in Fig. 2 looking in the direction of the arrows and showing also in dotted lines the 55 position of the central spindle or foot when the same is in place;

Fig. 4 is a side elevation of one of the pointers detached from the indicator;

Fig. 5 is a side elevation of the central spindle;

Fig. 6 is a side elevation of one of the plurality of feet; and

Fig. 7 is a perspective view of one of the pointers.

The board 1 is placed on the laps of two 65 persons, preferably a lady and a gentleman, the ends rather than the sides resting in their laps.

The indicator 2 is then placed at any point upon the operative surface of the board 1, 70 generally about its center.

This indicator may be equipped upon its underneath side either with the central spindle or foot 3, or with a plurality of feet 4, the studs 5 of which are inserted in the 75 sockets 6 in the underneath side of table or indicator 2. While four holes 6 are provided, this number may be varied to two or more.

The preferred form is the central spindle 80 or foot 3, the stud 7 of which is inserted in hole 8 and fits therein with sufficient tightness not to fall out.

The bottom of spindle 3 is convex at 9 and the bottom of each foot 4 is convex at 85 10. These convex parts greatly facilitate the movement of the indicator 2, making the same noticeably more responsive to the impulses that cause its movement as compared to other similar devices.

The bottom of feet 3 and 4 is tipped with 90 felt 11 and 12 respectively to prevent scratching of board 1, the operative surface of which is preferably polished.

The pointers 13 are attachable to the indicator 2, preferably by means of the jaws 14, which is simple and convenient, but other means may be used.

The advantage of the said pointers over 100 existing indicator tables of this kind is that there are two such pointers, so that either person of the pair using this apparatus can see what is indicated by the indicator, and moreover that the pointer directly reaches to the letter, number, word, or symbol imprinted upon the surface of board 1, and furthermore that it can easily be seen what it is to which such pointer points, it being more or less difficult with such apparatus now in common use to see exactly what is 105 indicated by the forefoot of the indicator table.

In the use of the indicator 2 the little fingers of each hand are placed upon the shoulders 15 and the thumbs caused to touch at approximately the intermediate spaces between the same, while the first, second and third fingers of each hand lightly touch the top of indicator 2, the contact of the little fingers and thumbs being also very light.

As is customary in this class of apparatuses the indicator 2 moves over the surface of board 1 as a result of the impulses that indicator 2 receives and the said movements result in one or the other of the pointers 13 indicating letters in succession that may spell a message, or words, or numbers, or a symbol for the same purpose. Some people get more out of these boards than others.

The recesses 16 are not only ornamental but convenient for receiving the jaws 14 of pointers 13 and also the little fingers of the operators.

The arrangement of the printed matter upon the surface of board 1 with a clear space in the center and the characters from which the answer is derived adjacent to its margin, makes it easier for both operators to see exactly what is indicated by the indicator 2.

Having thus described this invention, I hereby reserve the benefit of all changes in form, arrangement, order, or use of parts, as it is evident that many minor changes may be made therein without departing from the

spirit of this invention or the scope of the following claims.

I claim:

1. In a device of the character described a board having its indicia marginally disposed thereon and a clear space of substantial area surrounded by said marginally disposed indicia.

2. An indicator for an apparatus of the character described adapted to travel freely over the surface of the table, consisting of a disk having diametric recesses in its periphery, pointers secured in said recesses and projecting beyond the periphery of the disk, a support projecting from the under face of the disk; said recesses functioning to direct the position of the hands of the operator on the disk whereby the direction of the pointers is always visible.

3. An indicator table of the character described having a pair of recesses in its periphery, and pointers located respectively in the said recesses, the said pointers being each provided with a jaw adapted to grip the said disk.

4. An indicator table of the character described having a pointer provided with a jaw, which jaw is adapted to grip the body of the said table.

In testimony whereof I hereunto affix my signature.

DANIEL SULLIVAN.
